UNITED STATES PATENT OFFICE.

FRANK E. FARNHAM, OF PROVIDENCE, RHODE ISLAND.

EAR-RING.

No. 869,965.

Specification of Letters Patent.

Patented Nov. 5, 1907.

Application filed July 2, 1907. Serial No. 381,924.

To all whom it may concern:

Be it known that I, FRANK E. FARNHAM, a citizen of the United States, residing at Providence, in the county of Providence and State of Rhode Island, have 5 invented certain new and useful Improvements in Ear-Rings, of which the following is a specification, reference being had therein to the accompanying drawings.

Like reference letters designate like parts.

10 Figure 1 is an elevation of my improved ear ring, the imitation pearl and the setting of the same being shown in central diametrical section. Fig. 2 is a view of the resilient ear wire, as seen in side elevation. Fig. 3 is an end elevation of said wire. Fig. 4 shows in elevation 15 my improved ear ring in position upon the lobe of the ear.

My invention relates to that class of ear rings which are attached to the ear lobe by compressing the lobe by a resilient wire loop, thus avoiding the piercing of 20 the lobe as formerly customary for the insertion of an ear ring, or the attachment of an ear jewel.

My invention consists of the novel construction and arrangement of the parts hereinafter described, as set forth in the claims.

25 The ear wire is preferably made of gold, or gold-plated stock, and is designated as A in the drawings. It is bent into a curve, substantially as shown. The ear wire A has not only the intermediate or U-shaped bend a, but terminates at each end in a closed circular 30 loop, one of which loops is shown at a' and the other at a''. The tip comes into abutment with upper portion of the ear wire, as best seen at b in Fig. 3, but indicated also at b' in Figs. 1, 2 and 4. The closed loop end a' is also bent transversely into the concavo-convex form 35 shown in Figs. 1, 2, and 4.

B is an imitation pearl or bead of a general spherical shape on its exposed portion, as seen in Figs. 1 and 4. It is filled with any suitable substance, such as wax, the filling being marked C in Fig. 1.

40 D is a button or cup made of gold or gold-plated stock, struck up by a die and plunger from a disk of such metal in sheet form. The convex part of the button D projects towards the end or loop a'. The button D has an annular grooved neck or flange d. A washer 45 or disk E of metal has a central perforation, through which a screw F passes. The head f of the screw is preferably riveted to the disk E, and the threaded portion of the shank of the screw enters and is embedded in the filling C of the bead or imitation pearl B, thus 50 holding the same in place.

In assembling the earring, the screw F is inserted through the central aperture of the disk E, and the screw-head f is riveted in position. The disk E is then inserted in the cup D, while the annular flange is open 55 sufficiently for that purpose. By a suitable tool said

flange is concentrically bent in a radial inward direction, thereby inclosing and confining the disk E therein, the flange at that time being tubular. This flange is then inserted through the loop a'', and a suitable tool is used to form an outwardly flaring edge upon the 60 flange, as illustrated in Fig. 1, thereby making a circumferential groove on the flange, in which groove the loop a'' is seated and engaged.

The cup D is filled with cement or glue, as usual, and the bead or imitation pearl B is screwed or pushed 65 onto the projecting threaded end of the screw F, until it comes into close contact with the loop a'', as illustrated in Fig. 4. When the earring has thus been assembled, only gold surfaces remain exposed.

To attach the earring to the ear, the resilient ear wire 70 A is easily sprung outwardly, to slightly enlarge the space between the button D and the transversely bent circular loop a', and in this condition is pushed over the ear wire G, up along the ear lobe H (which in most persons is somewhat thinner than the ear rim G) until the 75 bend a of the ear wire A is in close proximity to the edge of the ear. When the ear wire A is released and allowed to spring back into its normal position, the button D presses the flesh of the lobe H inwardly and crowds a portion thereof into the aperture in the circular open loop a' of the opposite end of the ear wire A, as illustrated in Fig. 4, thus holding the earring firmly 80 in place upon the ear, but with so light a pressure as not to be noticeable.

I claim as a novel and useful invention and desire to 85 secure by Letters Patent:—

1. The improved ear ring herein described, consisting of the combination of a wire spring substantially U-shaped in form and provided with two looped ends; a button secured in one of said ends; a perforated disk in said button; a bead filled with a plastic material; and a screw mounted at one end in said disk and embedded at its threaded end in the filling of the bead. 90

2. The improved ear ring herein described, consisting of the combination of a wire spring substantially U-shaped and having at each end a circular loop, which loops are arranged opposite each other; a button mounted in one of said loops and extending inwardly; a bead mounted on said button and extending outwardly; and means for securing the bead in position upon the button. 95

3. The improved ear ring herein described, consisting of the combination of a wire spring substantially U-shaped and adapted to embrace an ear lobe above the lower rim of the ear and automatically to hold the ear ring in said position; a circular loop on each end of said wire, which loops are arranged opposite each other; a button mounted in one of said loops and extending inwardly; a bead mounted on said button and extending outwardly; and means for securing the bead in position upon the button. 105

4. The improved earring herein described, consisting of the combination of a U-shaped resilient ear wire; a circular loop on one end of said ear wire; a button mounted on the other end of said ear wire opposite to said circular loop; and a bead mounted on said button. 110

5. The improved ear ring herein described, consisting of 115

the combination of an ear wire; a button having a circumferentially grooved neck; a circular loop on one end of the ear wire surrounding the neck of the button in engagement with said groove thereof; and a bead mounted on said button.

6. The improved ear ring herein described, consisting of the combination of an ear wire; a button having a circumferentially grooved neck; a circular loop on one end of the ear wire surrounding the neck of the button in engagement with said groove thereof; a bead mounted on said button and in bearing contact with the circular loop and means of holding said bead in place upon the button and in contact with the circular loop.

7. The improved ear ring herein described, consisting of the combination of a U-shaped resilient ear wire; an integral circular loop upon one end of the ear wire bent transversely in a direction at a right angle to said ear wire; a button having a circumferentially grooved neck;

an integral circular loop upon the opposite end of the ear wire and surrounding the neck of the button in engagement with said groove thereof, which last named circular loop is opposite to the first named circular loop; a bead having a plastic filling; and a screw whose head is supported within said button and whose threaded shank is embedded in the plastic filling of the bead, all so arranged that the pressure of the button upon the ear lobe produced by the resilience of the ear wire causes the part of the ear lobe so pressed to enter into and fill the aperture of the transversely bent circular loop. 20 25

In testimony whereof I affix my signature in presence of 30 two witnesses.

FRANK E. FARNHAM.
